AUTOMOBILE DOORLATCH OPERATOR

Walter B. Craft, Tyler, Tex., assignor of one-fourth to Clarence M. Smith, Tyler, Tex.

Application May 9, 1933, Serial No. 670,173

4 Claims. (Cl. 292—173)

This invention relates to door latch operating means and pertains particularly to an improved handle structure or operator for the latch or bolt of a motor vehicle door.

5 The primary object of the present invention is to provide a bolt operator or handle for a motor vehicle door latch which is flush with the face of the door so that the danger of breaking the handle by striking it against some outside object, or of 10 catching the clothing therein, is avoided.

Another object of the invention is to provide 15 a motor vehicle latch bolt operating handle which is set in flush with the face of the door in which the latch is mounted so that the contour or stream line effect of the vehicle body remains unbroken.

20 Other objects and advantages of the invention will become apparent as the description of the same proceeds and the invention will be best understood from a consideration of the following detailed description taken in connection with the accompanying drawing forming part of this specification, with the understanding, however, that the invention is not confined to any strict conformity with the showing of the drawing but may be 25 changed or modified so long as such changes or modifications mark no material departure from the salient features of the invention as expressed in the appended claims.

In the drawing:—

30 Figure 1 is a view in horizontal section through a portion of a motor vehicle door and through the latch structure and operating means therefor which comprises the present invention, the section being taken substantially upon the line 1—1 35 of Figure 2;

Figure 2 is a vertical sectional view taken substantially upon the line 2—2 of Figure 1;

Figure 3 is a sectional view taken substantially upon the line 3—3 of Figure 1.

40 Referring now more particularly to the drawing wherein like numerals of reference indicate corresponding parts throughout the several views, the numeral 1 indicates a portion of a motor vehicle door, while a portion of the car body against which the free edge of the door closes is indicated by the numeral 2.

The inner and outer walls of the door are indicated respectively by the numerals 3 and 4 and 45 each of these walls has formed therein a handle opening 5. The handle openings 5 are preferably of substantially elongated rectangular contour, one end of which opening is rounded as indicated at 6. Formed integral with each wall of the door 55 at the rounded portion 6 of each handle opening

is a hood or shield 7 which is disposed within the area between the door walls as illustrated.

Within the openings 5 are the inner and outer handles 8 and 9 respectively which are in the form of plates of slightly less length than the openings in which they position but of substantially the full width of the opening. Each handle plate is rounded at one end as indicated at 10 and the rounded end is disposed in spaced relation with the rounded edge 6 of the opening in which the 10 handle is disposed.

For the sake of clearness and ease of description the rounded ends 10 of the handles will be referred to as the free or forward end, as each of the handles is pivotally mounted adjacent its 15 other end so that it may swing outwardly from the opening 5 in which it is disposed.

Each of the handles adjacent its free end has mounted upon its inner face the handle bar 11 which, when the handle is in closed position, 20 locates in the adjacent hood 7.

Adjacent the end remote from the handle bar 11, each handle carries the ears 12 which are adjacent the longitudinal edges thereof and connecting and passing through these ears is a 25 pivot bolt 13. At the top and bottom edge of each of the openings 5 there are secured to the adjacent walls the bearings 14 into which the pivot bolts 13 extend. The handles 8 and 9 are thus free to swing outwardly with respect to the 30 adjacent walls in which they are mounted.

In order to retain each handle in its opening 5 each of the pivot bolts 13 is surrounded by a coil spring 15, one end of which is secured to an ear 12 while the other end is secured either to the adjacent bearing 14 or the adjacent wall. It will thus be seen that when the handle is swung outwardly the spring will be twisted and placed under tension so that when the handle is released the 35 reactionary effect of the spring will swing the 40 handle back to the position in which both handles are shown in Figure 1.

Each of the handles 8 and 9 adjacent its pivoted end has an integral finger 16 extending inwardly from its end edge. This finger operates to shift 45 an adjacent bolt when the handle, of which it forms a part, is swung outwardly as will now be described.

Mounted upon suitable supporting and guide brackets 17 which are secured to the inner face of the door wall 4, is a reciprocable bolt 18. The forward end of this bolt passes through an opening 19 in the free edge of the door, for engagement in the aperture 20 of the keeper plate 21 which is secured to the face of the door frame. 55

This free end of the bolt is beveled in the usual manner as indicated at 22 so that the door will latch when it is permitted to swing to closed position.

5 The face of the bolt 18 which is in opposition to the outer handle 9, carries a lug 23 against one side of which the finger 16 of the adjacent handle 9 constantly bears.

The bolt 18 is constantly urged outwardly by 10 the leaf spring 24 which is mounted at one end in a suitable supporting bracket 25 which is secured to the inner face of the wall 4 in the manner shown.

Secured to the inner face of the wall 4 are 15 the vertically disposed aligned ears 26 which have their adjacent ends in spaced relation as shown in Figure 2. These ears form keeper members behind which the lugs 27 of a cylinder lock 28 engage when the lock is actuated to secure 20 the handle and the door against movement. In the position in which the lugs 27 are illustrated in Figures 1 and 2 the handle 9 is free to swing to the position indicated by dotted lines in Figure 1. As will be seen from this figure when 25 the handle 9 is swung outwardly to this position the integral finger portion 16 will exert a force against the lug 23 which will shift the bolt 18 rearwardly against the tension of the spring 24, thus permitting the door to be swung open. As 30 soon as the handle 9 is released the spring will react to force the bolt forwardly and the lug 23 operating against the finger 16 will swing the handle 9 back to closed position. This return movement of the handle 9 will be assisted and 35 assured by the spring 15 which is placed under tension when the handle is swung outwardly, in the manner previously described.

The handle 8 facilitates the unlatching of the 40 door from the inside of the car and this unlatching of the door is effected through the medium of an auxiliary bolt 29. This auxiliary bolt is slidably mounted in suitable supporting brackets 30 which are mounted upon the inner face of the inner wall 3.

45 The bolt 29 carries a lug 31 against which the finger portion 16 of the inner handle 8 normally bears and the end of this bolt which is nearest the free edge of the door bears against the lower end of a lever 32 which is mounted intermediate its ends upon the pivot pin 33 which in turn is supported by the wall 3. The upper end of this lever 32 engages the pin 34 which is carried by the bolt 18 so that when the auxiliary bolt 29 is shifted forwardly by the swinging of the inner handle 8 it will engage the lower end of the lever 32 and oscillate the same so that the upper end swings rearwardly against the pin 34 and thus retracts the bolt. As will be seen the leaf spring 24 operates to return the bolt 50 18 to its normal position after either handle has been operated. As will be readily seen from Figure 3 the inner handle 8 is mounted in the same manner as the outer handle and has a spring 13 which is placed under tension when it is swung outwardly, to return it to folded or inoperative position.

55 By providing the auxiliary bolt 29 with the stop pin 35 which abuts the adjacent guide 38, the return movement of the auxiliary bolt 29 is limited and this in turn limits the forward movement of the main bolt 18 under the urge of the spring 24.

70 From the foregoing it will be readily apparent that the present latch bolt operating handle will form an attractive addition to a car door and

will at all times remain in a position flush with the wall of the door so that all danger of catching the clothing thereon and of striking the handle in such a manner as to injure it or the mechanism with which it is connected, is avoided. 5

By the provision of the handle bars 11 upon the inner faces of the handles it will be readily apparent that in actuating either handle the fingers are inserted into the shields or hoods 7 and engaged behind the handle bars so that 10 when the handles are swung outwardly a grip will be had thereon which will facilitate the pulling of the door to open or closed position.

While the same has not been illustrated it will be readily apparent that means may be readily provided for preventing the passage of rain water or moisture from other sources into the interior of the door body between the handles and the edges of the openings in which they are located, as, for example, a rubber beading may be 20 applied to the edge of the handle for contact with the edge of the opening when the handle is closed. 15

Having thus described the invention, what is claimed is:—

25 1. Locking mechanism for a door, comprising a bolt reciprocably mounted in the door and having an end extending through an edge face thereof, resilient means normally urging the bolt in one direction, an auxiliary bolt mounted within 30 the door and shiftable in a line parallel with the first bolt, a pivotally mounted lever having one end engaging the first bolt and having its other end engaged by the auxiliary bolt, a handle carried by the body of the door and mounted to 35 swing on an axis extending transversely of the bolt and normally extending parallel with the side face of the door and connecting means between the handle and the auxiliary bolt whereby the longitudinal movement of the latter will be effected upon the swinging of the handle toward a position where it extends outwardly from said side face. 40

2. In a door structure, inner and outer walls having openings therein, a handle plate pivotally 45 mounted in each opening, said plates being swingable in the same direction, means facilitating the grasping of said plates to swing the same outwardly, a bolt reciprocably mounted within the door to extend across one plate, coupling means 50 between said bolt and the said one plate, a bar reciprocably mounted within the door to extend across the other plate, coupling means between said bar and the said other plate whereby the bar will be shifted by the said other plate in a direction opposite to the movement of the bolt by the plate coupled therewith, an elongated member pivotally mounted intermediate its ends within the door and having one end in opposed relation to an end of said bar, to be swung by the bar in 55 the movement of the latter by the plate coupled therewith, a pin carried by the bolt and engaged by the other end of the arm whereby movement of the arm by the bar will effect the retraction of the bolt, and resilient means normally urging 60 the bolt into operative position and urging said pin against the adjacent arm. 65

3. In a door structure, inner and outer walls having openings therein, a handle plate pivotally mounted in each opening, said plates being swingable in the same direction, means facilitating the grasping of said plates to swing the same outwardly, a bolt reciprocably mounted within the door to extend across one plate, coupling means 70 between said bolt and the said one plate, 75

a bar reciprocably mounted within the door to extend across the other plate, coupling means between said bar and the said other plate whereby the bar will be shifted by the said other plate in a 5 direction opposite to the movement of the bolt by the plate coupled therewith, an elongated member pivotally mounted intermediate its ends within the door and having one end in opposed relation to an end of said bar, to be swung by the bar in the 10 movement of the latter by the plate coupled therewith, a pin carried by the bolt and engaged by the other end of the arm whereby movement of the arm by the bar will effect the retraction of the bolt, and a leaf spring secured at one end within the 15 door body and having its other end coupled with said bolt and normally urging the same in the opposite direction to which it is moved by the plate coupled therewith and normally urging the pin against said arm to urge the bar in a direction 20 opposite to its direction of movement by the plate with which it is connected.

4. In a door, side walls each having a horizontally disposed elongated opening therein, outwardly opening shells disposed within the door body and connected with remote end edges of said openings, an elongated handle plate in each opening pivotally attached at the end remote from the shell-like body and having the opposite end terminating short of the adjacent end of the opening whereby the fingers may be inserted behind the plate into the shell-like body, a finger 10 bar disposed transversely of each plate in a position to be normally housed in the adjacent shell-like body, said handle plates being mounted to swing in the same direction, a bolt reciprocably mounted within the body of the door, and mechanism coupling the handle plates with said bolt whereby the swinging of either will effect the retraction of the bolt. 15
